(57) **CLAIM**

The ornamental design for a mass airflow housing as shown and described.

DESCRIPTION

FIG. 1 is a front, left side, perspective view of the mass airflow housing.

FIG. 2 is a front view of the mass airflow housing.

FIG. 3 is a rear view of the mass airflow housing.

FIG. 4 is a left side view of the mass airflow housing.

FIG. 5 is a right side view of the mass airflow housing.

FIG. 6 is a top view of the mass airflow housing.

FIG. 7 is a bottom view of the mass airflow housing; and, FIG. 8 is a front, right side isometric view of the mass airflow housing.

In the drawings, the broken lines depict subject matter that forms no part of the claimed design.
